Primary Examiner — Sheryl Lane(74) Attorney, Agent, or Firm — Paul R. Martin(57) CLAIM

The ornamental design for a hand held rock picker, as shown and described.

DESCRIPTION

FIG. 1 is a perspective view of the hand held rock picker of my new design.

FIG. 2 is a front elevational view thereof. The view from the back is a mirror image of the front elevational view.

FIG. 3 is an elevational view of the right side thereof. The view from the opposite side is a mirror image thereof.

FIG. 4 is a top plan view thereof; and,

FIG. 5 is a bottom plan view thereof.
